UNITED STATES PATENT OFFICE

113,174

DESIGN FOR A COMBINED HOSE NOZZLE AND HANDLE

Cecil H. Smith, Elmira, N. Y., assignor to American-La France-Foamite Corporation, Elmira, N. Y., a corporation of New York

Application September 17, 1938, Serial No. 79,962

Term of patent 14 years

To all whom it may concern:

Be it known that I, Cecil H. Smith, a citizen of the United States, residing at Elmira, in the county of Chemung and State of New York, have invented a new, original, and ornamental Design for a Combined Hose Nozzle and Handle, of which the following is a specification, reference being had to the accompanying drawing, forming a part thereof.

The figure is a perspective view of a combined hose nozzle and handle showing my new design, the remote side having substantially the same appearance as the side shown except for the omission of the handle.

I claim:

The ornamental design for a combined hose nozzle and handle, as shown and described.

CECIL H. SMITH.
